PROCESS FOR THE PYROLYtic DECOMPOSITION OF HYDROCARBONS

Filed March 12, 1932

UNITED STATES PATENT OFFICE

2,046,501

PROCESS FOR THE PYROLYtic DECOMPOSITION OF HYDROCARBONS

Maurice B. Cooke, New York, N. Y.

Application March 12, 1932, Serial No. 598,503

1 Claim. (Cl. 196—67)

My invention relates to a process for the pyrolytic decomposition of hydrocarbons to form gasoline-like hydrocarbons suitable for using as a motor fuel having high antiknock qualities.

5. The process is usually known as a "cracking" process and relates more particularly to the cracking of hydrocarbons in the vapor phase by hot gases of combustion.

When fuel is burned with no excess of air, the 10 temperature of combustion is between 3,000° and 4,000° F. These temperatures are too high for efficient cracking and accordingly they must be tempered or brought down to about 1,500° F. in order to give an efficient cracking process.

15. In an application of William O. Keeling, Serial No. 586,573, a method of tempering the combustion gases by means of a cooler, inert gas is disclosed.

This application relates to an improvement 20 in my copending application Serial No. 598,502, filed March 12, 1932 now patent No. 2,016,798 issued October 8, 1935 to Maurice B. Cooke.

When a great volume of gas is introduced into the fractionating tower, many disadvantages result. The equipment must be made a larger size. 25 The volume of gas to be compressed for absorption purposes is so increased that the process becomes expensive. The use of a cool, inert gas to temper the combustion gases represents a direct loss of heat besides increasing the volume of the 30 gases to be handled.

One object of my invention is to avoid the disadvantages above pointed out, with special reference to reducing the volume of the gas to be 35 handled by the fractionating equipment.

It will be noted that the instant invention differs from my above mentioned co-pending application in that all the vapors, gases and the like emanating from the reaction zone are cooled and 40 condensed and the fixed gases are to be removed therefrom. The condensed material is to be reheated and passed to the fractionating zone where the gasoline-like hydrocarbons are separated from the gas oil and other heavier hydrocarbons.

A further object of my invention is to provide a process in which fractionating equipment of small dimensions may be used due to the fact that no considerable amount of flue gas or fixed 45 gas passes through the fractionating zone.

Another object of my invention is to provide a process in which the hot gases of combustion are tempered by means of heat exchange.

50. A further object of my invention is to employ the gas heat for topping the charging stock, va-

porizing the charging stock for conversion into the vapor phase and supplying heat for other purposes such as distilling the oil or the generation or high superheating of steam.

Still another object of my invention is to provide a vapor phase cracking process in which hot gases of combustion are used to supply the cracking heat which is flexible of control and efficient in operation.

Still another object of my invention is to check 10 the reaction to prevent over-cracking by means of shock chilling the products of reaction.

Other objects of my invention will appear from the following description:

The figure shows a diagrammatic view of one 15 embodiment of the process of my invention.

In general, my invention consists in burning fuel and air with surface combustion in a furnace to supply hot gases of combustion substantially devoid of free oxygen. I charge crude oil from storage to suitable heat exchangers through a coil situated within the furnace. The temperature of the hot gases of combustion will be lowered and lose part of their heat in heating the incoming charge during its passage through the topping 25 heating coil. The heated products are discharged into a fractionating tower preferably of the bubble type, whence the vapors are withdrawn overhead, condensed and passed into a separator. The gasoline is withdrawn from the separator and 30 passed to storage. A heavier fraction collects in the separator and is refluxed into the bubble tower. The reflux condensate from the bubble tower may be pumped to storage and forms the cracking stock which is used in my process. The 35 reflux condensate may, if desired, be pumped directly through suitable heat exchangers into an accumulator tank. Oil is pumped from the accumulator tank through suitable heat exchangers, through a second coil situated in my furnace 40 where the heat necessary to convert a substantial portion of the charging stock into vapors is supplied. The heated charging stock is passed into a flash evaporator whence the vapors are withdrawn and passed to the cracking zone. In the 45 cracking zone the vaporized hydrocarbons encounter the hot gases of combustion which have been tempered to about 1,500° F. The hot gases of combustion admixing with the vapors bring the mixture to about 1,100° F. at which temperature cracking takes place rapidly. The increase in volume is accommodated for by a progressively increasing cross sectional area. After leaving the cracking zone, the products of the reaction 50 are shock chilled by means of an oil spray.

The products, after being chilled, pass into a tar separator. The tar laden quenching oil is drawn through a cooler and pumped to storage and may be used for fuel oil. The vapors and gases are 5 passed through a sectional entrainment condenser through suitable heat exchangers and into a separator, whence the uncondensed gases are withdrawn overhead and allowed to pass into the gas main. It will be noted that this is the novel 10 step in which the excess and uncondensed gases are withdrawn from the system in order to prevent their being passed through the fractionating tower. The condensate is then pumped in heat exchange with the hot products to re-vaporize 15 the condensate and in vaporized condition it is passed into a fractionating tower. The entrainment condensate from the condenser collects in suitable pockets and may be passed either into the separator or into a fractionating tower depending upon their nature and character. 20

The reflux condensate from the fractionating tower is withdrawn and pumped through a cooler in order to reduce the temperature thereof to render it suitable as a quenching medium. After 25 passing through the cooler, it is passed through the sprays in order to be used in the chilling zone. A portion of the reflux condensate from the fractionating tower may be diverted into the accumulator for recycling. The vapors withdrawn from 30 the fractionating tower are cooled and passed into a separator from which the water is withdrawn. The uncondensed vapors from the separator are compressed and cooled and passed into a receiver. The condensate is withdrawn as gasoline 35 and passed to storage.

More particularly, referring now to the drawing, the crude oil from storage is charged through line 1 and pumped by pump 2 through heat exchanger 3, through heat exchanger 4, through 40 topping heating coil 5, where the crude oil being charged is heated. The heat imparted to the incoming crude lowers the temperature of the combustion gases. The oil leaves the topping heating coil through line 6 and is charged into the fractionating tower 7. This tower is preferably of the bubble type but it is to be understood that any suitable fractionating column may be employed. The topped oil is withdrawn through line 45 8 and pumped by pump 9 through heat exchanger 4. If valve 10 be closed, and valve 11 be opened, the oil will pass through cooler 12 into storage 13. The cooler 12 is cooled by circulating water or any suitable means. The pump 50 14 will pump oil from the cracking stock storage tank 13 if valve 15 be open. If valve 10 be open and valve 11 closed, the topped crude will pass through line 16 into line 17 to pump 14.

The vapors from the bubble tower 7 are withdrawn through line 18, through heat exchanger 3 into cooler 19 where it is condensed. The condensate passes through line 20 into separator 21. The gasoline is withdrawn through line 22 and passed to storage. A heavy fraction is withdrawn 60 from the separator through line 23 by pump 24 and pumped back into the bubble tower 7 as a reflux. The topped crude is pumped by pump 14 through heat exchanger 25, through heat exchanger 27, whence it passes through line 28 into the accumulator 29. The charging stock thus preheated is withdrawn through line 30 by pump 31 and is pumped through line 32. The products of combustion in the furnace are tempered by losing some of their heat to the charging stock 65 passing through coil 40. The heated charging

stock leaves the coil 40 through line 41 and passes into the flash evaporator 42. The unvaporized oil from the flash evaporator may pass through line 43, through valve 44, through line 47, through cooler 49, where it is pumped by pump 50 to storage as fuel oil. The oil vapors from the flash evaporator will pass through line 51 in the form of vapors and be discharged into a mixing zone 52. Valve 51' controls the vapor flow.

Gas is withdrawn from the gas main 53 through branch line 54 and compressed by compressor 55 into gas supply tank 56, whence gas is withdrawn through line 57 being controlled by valve 58 into the mixing chamber 59' of a surface combustion burner. Compressed air, 15 controlled by valve 61', also passes into the mixing chamber 59'. The mixture burns with surface combustion about the refractory granules 62' of the surface combustion burner 63'. The hot gases of combustion will pass into the furnace 64' and be tempered by heat exchange with the material passing through coils 40 and 5 respectively and into the mixing zone 52, whence a commingling of the hot products of combustion so tempered to about 1,500° F. will 25 take place with the hydrocarbon vapors coming from the flash evaporator 42. After admixture, the temperature will be about 1,100° F. and cracking or pyrolytic decomposition will take place rapidly. 30

As cracking takes place, the volume of the products will increase and, in order to prevent the building up of pressure, a cracking chamber of progressively increasing volume is provided.

Inasmuch as the cracking will take place very 35 rapidly, at the temperature of 1,050° F., I resort to shock chilling or quenching to reduce the temperature of the products of reaction from 1,100° F. to 700° F. I do this by means of oil sprays 53', 54', and 56', oil spray 56' being located in 40 the tar separator 57. The temperature of 700° F. is low enough to prevent any further reaction and high enough to permit the distillate to escape in the vapor state into the fractionating tower. The heavy, tarry fuel oil, however, will 45 accumulate in the bottoms of the separator 57. This tar laden oil is withdrawn through line 58 which joins with line 47 and permits the fuel oil bottoms to be passed through the cooler 49 to fuel oil storage. 50

The vapors and gases from the tar separator 57 pass overhead through line 59 into a sectional entrainment condenser 37, whence they will pass in counterflow relation to the condensate from separator 33 which is passing through tubes 36. 55 The hot vapors will be cooled considerably by the condensate which in turn will be heated. The condensate is allowed to collect in compartments 60, 61 and 62. The condensate may be withdrawn from the respective compartments 60 and selectively passed into the separator or fractionating tower through lines 63 and 64 respectively. The entrainment condensate may be supplied as desired by means of valves 65, 66, 67 and 68, so that all or part of the condensate collected in the sectional entrainment condenser 37 may be passed to either the separator or the fractionating tower as desired and depending upon the nature of the condensate. The vapors leave the sectional entrainment condenser through line 69 and pass through heat exchanger 34, through cooler 35 and into separator 33. The uncondensed gases escape from the separator 33, through line 38 and pass into gas main 53. The condensate is pumped from the 70 75

separator 33 by pump 39 through line 45 through heat exchanger 34 through line 46 through the tubing 36 of the sectional entrainment condenser 36 where the heat of the vapors coming through 59 will revaporize the condensate. It will be appreciated that by withdrawing the fixed gases before the fractionating tower that I may use fractionating equipment of smaller dimensions and am enabled further to eliminate the expense 10 of compressing a large quantity of gas during gasoline absorption treatment.

The vaporized condensate passes through line 48 into fractionating tower 70.

The reflux condensate from the fractionating tower is withdrawn through line 71 and passed through heat exchanger 27, through line 72, through pump 73, through cooler 14 and through line 75 which terminates in a manifold for the quenching sprays. The quenching oil leaves line 15 75 through valve controlled lines 77, 78 and 80. If desired, a portion of the bottom from the fractionating tower may be diverted through valve controlled line 81 and allowed to pass into the accumulator for recycling.

The vapors from the fractionating tower pass through line 82, through heat exchanger 25, through cooler 83, through line 84 into separator 85. The water condensed from the stripping steam is withdrawn through line 86. The gasoline-like hydrocarbons are withdrawn through line 87 and passed to storage. The uncondensed vapors from the separator will contain a quantity of gasoline-like hydrocarbons. Accordingly, I propose to withdraw it through line 88 and compress the vapor in compressor 89, pass it through cooler 90 into receiver 91. The cooling and compressing will precipitate gasoline-like hydrocarbons which are withdrawn through line 92 and pass into line 87 to storage.

It will be appreciated that my process has many advantages. I temper the hot products of combustion by means of heat exchange and use the heat obtained by tempering to perform useful steps in my process. The thermal efficiency of my process will be exceedingly high. The flexibility of control is manifest. The temperature of the combustion gases, the temperature of the quenching oil and hence the temperature of reaction may be controlled within close limits. I am enabled by my process to crack hydrocarbon oil in the vapor phase and obtain a gasoline-like hydrocarbon suitable for use as a motor fuel and having an exceedingly high antiknock value. I may use a portion of the gas formed in my process for other purposes where gaseous fuel may be needed. It will be noted that the cracking reaction takes place in the pure vapor phase, it being impossible for any hydrocarbon oil which is not in the vapor form to be present. This insures the absence of the danger of the formation of coke or carbon deposits within my cracking zone. It will be understood, of course, that suitable lagging is provided throughout the piping and the piece of apparatus used in my process to prevent the loss of

heat by radiation. By withdrawing a large quantity of the gas from the system before fractionating the products of combustion, I am enabled to avoid large fractionating equipment and to dispense with the necessity of treating 5 a disproportionate amount of gas in gasoline absorption treatment.

It will be understood that certain features, sub-combinations and operations are of utility and may be employed without reference to other 10 features and sub-combinations. This is contemplated by and is within the scope of my claim. It is further obvious that various changes may be made in details within the scope of my claim without departing from the spirit of my invention. It is, therefore, to be understood that my invention is not to be limited to the specific details shown and described.

By this method of cracking hydrocarbons in the vapor phase, in which the hydrocarbons are 20 combined with the combustion gases, the latter being maintained at selected, controlled temperatures of reaction, a motor fuel having a high octane number and high antiknock value is obtained. The process eliminates parasitic crack- 25 ing which accompanies conventional cracking methods, in which the hydrocarbons are converted in tubular containers and heated by external circulation of the combustion gases thereabout. The intimate mixture of the combustion 30 gases with the hydrocarbon vapor produces a distribution of heat impossible with the conventional tubular cracking processes.

Having thus described my invention, what I claim is:

The process of treating hydrocarbon oil to form hydrocarbons of lower molecular weight which includes the steps of generating hot combustion gases, passing relatively heavy oil charging stock in indirect heat exchange with said 40 hot combustion gases to reduce the temperature thereof, subjecting the relatively heavy oil charging stock thus heated to a topping operation, passing the topped oil as the hydrocarbon oil to be cracked, in indirect heat exchange with 45 said combustion gases to lower the temperature thereof, flashing the oil thus heated into vapors in a vaporizing stage, directly commingling said vapors with said tempered products of combustion, permitting a pyrolytic decomposition of 50 said hydrocarbon vapors to take place to form hydrocarbons having a lower molecular weight, and stopping said reaction by spraying cooler quenching oil into the reacting vapors after the reaction has progressed a desired extent whereby 55 over-cracking is prevented, cooling the products of reaction, separating the uncondensed fixed gases from the condensate in a separating stage from which the uncondensed fixed gases and condensate are separately withdrawn, revaporizing the 60 condensate, fractionating the vapors in a fractionating stage, and withdrawing reflux condensate from the fractionating stage for use as the quenching oil.

MAURICE B. COOKE. 65
